UNITED STATES PATENT OFFICE.

HENRY T. WATTS, OF YOUNGSTOWN, OHIO.

GAS BURNER.

Application filed July 23, 1920. Serial No. 398,399.

To all whom it may concern:

Be it known that I, HENRY T. WATTS, a citizen of the United States, residing at Youngstown, in the county of Mahoning and State of Ohio, have invented a new and useful Improvement in Gas Burners, of which the following is a full, clear, and exact description.

The present invention relates to gas burners and more particularly to gas burners for heating purposes such, for example, as burners for furnaces.

One object of the invention is to so direct the streams of gas and air that a thorough mixture may take place.

The invention also relates to certain other combinations and arrangements of the parts, the advantages of which will be apparent to those skilled in the art from the following description, and which are more particularly pointed out in the claims.

In the drawings, in which is illustrated one embodiment of my invention,—

Figure 1 is a plan view of the burner and gas supplying pipe.

Figure 2 is a side elevation of the burner showing its relation to the furnace.

Figure 3 is a detail view showing one of the side plates.

Figure 4 is a detail view showing one end portion of the mixing chamber removed.

Figure 5 is a side elevation, partly in section, of the burner, and

Figure 6 is a detail view showing one of the orifice plates removed.

Referring to the illustrated embodiment of the invention, reference numeral 2 indicates the furnace which is gas-fired. The flame is discharged into the combustion chamber 3 through the door or opening 4.

The gas burner, indicated generally by reference numeral 5, is bolted on and supported by a gas supply pipe 6 which extends along in front of the furnace. The burner 5 is a laterally long burner, as shown in Figure 1, so that it discharges a thin wide flame into the combustion chamber of the furnace. The burner comprises a laterally long gas conduit or box 7, which is horse-shoe shaped in cross-section, as shown in Figures 2 and 5. The gas from the supply pipe 6 divides into the two branches of this horse-shoe shaped box and issues from two convergingly directed nozzles at

the ends of these branches, so that the two streams of gas impinge on each other. As shown in the drawings, the two streams of gas impinge at an angle of about sixty degrees to each other. The nozzles are formed by thin orifice plates 8, one of which is shown in detail in Figure 6. Each orifice plate has a laterally long narrow nozzle opening 9. The orifice plates fit into slots cut in the inner faces of the gas conduits and are readily removable so that orifice plates having different sized orifices may be readily used. The gas through the nozzles is discharged into a short mixing chamber 10 which is a laterally long rectangular box open front and back. The mixing chamber 10 is supported by being bolted to the side plates 11, one of which is shown in Figure 6. The side plates 11 are supported by being bolted to the sides of the gas box 7. The mixing chamber 10 is spaced from the ends of the branches of the gas box 7 to leave air intakes, indicated at 12, 13, 14 and 15. The air intakes 12 and 15 are at the outside (upper and lower sides) of the two converging gas streams. These air intakes are controlled by dampers 16 by means of which the proportions of the air and gas may be varied. The air intakes 13 and 14 lie between the converging streams of gas. The air is supplied to the intakes 13 and 14 through the open space or passage 17 through the inside of the horseshoe shaped box 7. This permits the air to be supplied to the inside as well as the outside of the converging gas streams and also serves to keep the gas box 7 cooler. A pipe 18 is located between the two streams issuing from the gas nozzles 9. This pipe serves as a deflector to cause the air from the space or passage 17 to divide into two streams, going through the intakes 13 and 14 respectively, and impinging on the streams of gas from their inner sides. The pipe 18 has a number of perforations 19 on the side toward the mixing chamber 10. Steam or air under high pressure may be supplied to the pipe 18 to increase the velocity of flow through the mixing chamber. When blast furnace gas is used, the pressure varies considerably, and there are certain times in the cycle of blast furnace operation that the pressure on the gas is very low so that the velocity through the mixing chamber might be less

than that of the flame propagation. Under such circumstances, steam or air may be blown through the orifices 19 in the pipe 18 to increase the velocity of flow through the mixing chamber 10.

The parts are so arranged that the air and gas mixture flows through the mixing chamber 10 at a velocity above the so-called critical velocity. Below the critical velocity the air and gas travel in lanes and do not readily mix. Above the critical velocity eddy currents are set up which cause a thorough mixture of the air and gas. The mixing chamber 10 is short so as to offer a minimum of resistance to the mixture flowing through it; and the gas nozzles and air intakes are arranged to cause a thorough mixture. The flow of gas through a thin plate orifice tends to cause eddy currents which assist in mixing the air and gas. It will be noted that the nozzles are convergingly directed so that the two streams of gas impinge on each other in the mixing chamber at an angle of about sixty degrees. This assists in causing a turbulent flow and thorough mixture. The air intakes are so arranged that the air is admitted at each side of each of the gas streams and flows inwardly so as to impinge against the gas streams in a manner permitting an easy and thorough mixing of the air with the gas. A thoroughly mixed stream of air and gas is discharged from the mixing chamber 10 at a velocity above that of flame propagation so that the flame does not flash back into the mixing chamber. As above pointed out, if the gas pressure falls, the velocity may be maintained above that of the flame propagation by admitting some gaseous fluid, such as steam or air, through the orifices 19 of pipe 18.

The parts are so arranged that the proper amount of air for complete combustion is drawn through the air intakes for different pressures of gas over the normal pressure changes, which occur on the gas supplies of industrial plants, such for example as steel plants supplied with blast furnace or coke oven gas. The gas and air flow may be adjusted for different qualities of gas by inserting different orifice plates 8 and by adjusting the air dampers 16.

While I have specifically illustrated and described the preferred embodiment of my invention, it is to be understood that the invention is not limited to the illustrated details of construction, but may be embodied in other constructions of gas burners within the scope of the following claims:

I claim:

1. A gas burner, comprising two convergingly-directed laterally long gas nozzles, a pipe between the gas streams issuing from the nozzle and serving as a deflector, said pipe having orifices through which a gaseous medium may be discharged at high pressure

if desired to assist the flow of gas, and a mixing chamber into which the gas together with air is discharged, substantially as described.

2. A gas burner having a mixing chamber, and means for forming a plurality of separate mixed air-gas streams and directing said mixed streams at an acute angle to each other into said mixing chamber for further mixing, substantially as described. 70

3. A gas burner having a mixing chamber, and means for forming a plurality of separate mixed air-gas streams and directing said mixed streams into said mixing chamber for further mixing, said means and chamber being so proportioned and arranged that the air-gas streams are discharged into said chamber at a velocity above the critical velocity whereby a turbulent eddy flow is maintained in the mixing chamber, substantially as described. 80

4. A gas burner, comprising a plurality of air and gas mixers, each comprising a gas nozzle and an air inlet at each side thereof whereby the gas is mixed with air impinging on each side of the gas stream, said mixers being arranged to form a plurality of converging mixed air-gas streams, and a mixing chamber into which the air-gas streams are directed so as to impinge on each other at an angle to form a turbulent mixing stream, substantially as described. 90

5. A gas burner, comprising a plurality of air and gas mixers, each comprising a gas nozzle and an air inlet at each side thereof whereby the gas is mixed with air impinging on each side of the gas streams, said mixers being arranged to form a plurality of converging mixed air-gas streams, and a mixing chamber into which the air-gas streams are discharged at a velocity above the critical velocity whereby a turbulent eddy flow is maintained in the mixing chamber, substantially as described. 100

6. A gas burner, comprising two air and gas mixers, each comprising a laterally long gas nozzle and a laterally long narrow air inlet, said mixers being arranged to form two separate converging sheet-like air-gas streams, and a laterally long mixing chamber into which the air-gas streams are directed so as to impinge on each other at an angle to form a turbulent mixing stream, substantially as described. 110

7. A gas burner, comprising two air and gas mixers, each comprising a laterally long narrow gas nozzle and air inlets along each side thereof whereby the gas is mixed with two impinging air streams, said mixers being arranged to form two converging mixed air-gas streams, and a mixing chamber into which the two air-gas streams are directed so as to impinge at an angle so as to form a turbulent mixing stream, substantially as described. 120

8. A gas burner comprising two air and gas mixers, each comprising a laterally long gas conduit having a slotted plate at the end thereof which suddenly reduces the area of the gas path so that the velocity of the gas is suddenly increased, and an air inlet at the side of the nozzle slot, said mixers being arranged to form two converging mixed air-gas streams, and a mixing chamber into which the two air-gas streams are directed so as to impinge on each other at an angle to form a turbulent mixing stream, substantially as described.
9. A gas burner, comprising an air and gas mixer having a gas conduit closed by a slotted plate which suddenly decreases the area of the gas path so that the velocity is suddenly increased, and an air inlet at the side of the nozzle slot for mixing air with the gas, substantially as described.
10. A gas burner, comprising a generally horse shoe shaped gas conduit having laterally long gas passages in its open ends, and providing an air passage between the two branches of the gas conduit, and inlet openings for admitting air from said air passage to the inner sides of the gas streams and for also admitting air to the outer sides of the gas streams, whereby independently mixed converging streams of air and gas are formed and caused to impinge upon each other, substantially as described.
11. A gas burner, comprising a gas conduit having two branches provided with laterally long narrow convergingly-directed gas nozzles, means for admitting air between the branches of the gas conduit to supply air to the inner sides of the gas streams, and means for also supplying air to the outer sides of the gas streams, whereby converging streams of mixed air and gas are

formed and brought together for further mixing, substantially as described.

12. A gas burner, comprising two gas passages having slotted plates forming laterally long convergingly-directed gas nozzles, the area of each slot being less than the area of the gas conduit so that the velocity of the gas is suddenly increased at the nozzle slot, so as to cause an eddy flow of gas from the nozzle slots, means for supplying air at the side of each gas stream so as to form two sheet-like convergingly-directed mixed air-gas streams, and a mixing chamber into which the air-gas streams are directed so as to impinge on each other at an angle for further mixing, substantially as described.

13. The method of mixing air and gas, which consists in separately mixing a plurality of air and gas streams at an acute angle to each other, and impinging said mixed streams in a mixing chamber to further mix said air and gas.

14. The method of mixing air and gas, which consists in separately mixing a plurality of air and gas streams, and bringing said mixed streams together at an acute angle to each other in a mixing chamber at a velocity above the critical velocity to further mix the gases.

15. The method of mixing air and gas, which consists in forcing a plurality of gas streams through long narrow openings, admitting air from each side of each of said gas streams adjacent said openings, and bringing said streams of mixed air and gas together at a sharp angle to each other to intermingle said streams of mixed air and gas.

In testimony whereof, I have hereunto set my hand.

HENRY T. WATTS.
